The ornamental design for a fruit dehydrator, as shown and described.

DESCRIPTION

FIG. 1 is a left front perspective view of a fruit dehydrator showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The structural features depicted by broken lines have been shown for the purpose of illustrating portions of the fruit dehydrator which form no part of the claimed design.
